CHARLES D. McARTHUR, OF PITTSBURGH, PENNSYLVANIA, ASSIGNOR TO BLOW STEEL CONSTRUCTION COMPANY, A CORPORATION OF NEW JERSEY.

FORM FOR CONCRETE CONDUIT CONSTRUCTIONS.

1,291,042.

Specification of Letters Patent.

Patented Jan. 14, 1919.

Application filed February 12, 1917. Serial No. 147,983.

To all whom it may concern:

Be it known that I, CHARLES D. McARTHUR, a citizen of the United States, residing at Pittsburgh, in the county of Allegheny and State of Pennsylvania, have invented certain new and useful Improvements in Forms for Concrete Conduit Constructions, of which the following is a specification.

10 The invention relates to forms for use in making concrete pipe or conduits, and has for its principal objects; the provision of a construction whereby metal "water stops" can be conveniently inserted at intervals throughout the length of the pipe; and the provision of a construction in which the water stop members can be inserted as the pipe is continuously formed, instead of requiring that the sections of pipe be formed alternately 15 using bulkheads as has heretofore been the practice. One embodiment of the invention is illustrated in the accompanying drawings, wherein—

Figure 1 is a cross-section through a completed conduit with a part of the apparatus in elevation, the section being taken on the line I—I of Fig. 2; Fig. 2 is a longitudinal section through the form before the concrete is applied; and Fig. 3 is a longitudinal section through a section of the completed conduit, the form being removed.

As indicated in Fig. 2 the form or mold comprises an outer form, two of whose sections 1 and 2 are shown, and an inner form, 25 two of whose sections 3 and 4 are shown. The sections 3 are each made in two parts to permit of collapse and removal, the parts being held together by the angles 3^a and bolts (not shown). The outer form sections 40 are secured together by means of the angle irons 5 which are riveted to the shells 1 and 2 and whose abutting flanges are secured together by means of bolts, not shown.

The inner sections 3 and 4 are provided 45 with angle irons 6 corresponding to the angle irons 5 and riveted to the shells 3 and 4, but their upright flanges are spaced apart to receive the series of plates 7 shown in Figs. 1 and 2.

50 As indicated in Fig. 1, the plates 7 together with the plates 8, which are of slightly different form, constitute an annular ring, which ring serves as a support

for the water stop member 9, such member being preferably of copper and provided 55 with the crimp 10. The plates 7 and 8 are clamped between the flanges of the angles 6, such flanges being secured by means of bolts (not shown), which pass through the holes 11 in the plates 7 and 8 (Fig. 1). 60

In operation the parts are assembled as indicated in Fig. 2, and the space between the outer and inner forms is filled with concrete, such concrete being supplied through the outer form, the upper sections of which 65 are removed to provide the necessary admission space. After the necessary amount of concrete has been filled in, the top plates are put in and the concrete allowed to set. After the concrete has set, the outer and inner forms are removed by disassembling them, the bolts through the flanges of the angles 6 being removed to release the plates 7 and to disconnect the sections 3 and 4. The plates 7 and 8 are then removed, the 70 plates 8 being first removed. This removal is facilitated by reason of the cut out portion 12 (Fig. 1), such cut out portion being fitted with a plate or board during the filling operation to prevent the escape of concrete at such time.

When the parts are thus disassembled the copper water stop 9 is left embedded in the pipe as indicated in Fig. 3, the slot formed by the removal of the plates 7 and 8 being 85 filled with the grout 13. In order to prevent the grout from filling the crimp 10 in the water stop, such crimp can be first filled by means of rope or other similar material.

By the use of the apparatus as above set 90 forth the conduit or pipe can be easily and conveniently constructed with the water stops at any desired intervals, the operation, in so far as the handling of the inner and outer form sections is concerned, being sub-

stantially the same as if no water stops were employed, which operation is much simpler and easier than where the conduit is made in alternate sections with the use of bulkheads at the end of each section to facilitate 100 the positioning of the water stops. In case the conduit cracks due to expansion or contraction, the rupture will occur opposite the crimp of the water stop as this is the thinnest and weakest point in the conduit, and 105 no damage will result since the water stop

will prevent leakage at this point. Other advantages incident to the use of the apparatus will readily be apparent to those skilled in the art.

5. What I claim is:

1. In combination in a conduit form, an outer form, an inner sectional form, and removable means carried at the joints of the inner form and adapted to support a metal water stop member lying between the two forms.
  2. In combination in a conduit form, an outer form, an inner sectional form comprising two abutting sections, and a member held between the said abutting sections and adapted to support a water stop member lying between the two forms opposite the said abutting ends.
  3. In combination in a conduit form, an outer form, an inner sectional form comprising two alined sections with their opposing ends spaced apart, a series of supporting plates lying between the said opposing ends of the inner sections and adapted to support a water stop member lying between the two forms, and means for securing the said opposing ends of the inner sections together with the supporting plates held therebetween.
  4. In combination in a conduit form, an outer form, an inner sectional form comprising two alined sections with their opposing ends spaced apart, a series of supporting plates lying between the said opposing ends of the inner sections and adapted to support a water stop member lying between the two forms, and means for securing the said opposing ends of the inner sections together with the supporting plates held therebetween.
- 10 15 20 25 30
5. In combination in a conduit form, outer and inner sectional forms, and removable supporting means carried at the joints of one of said forms and adapted to support water stop members.
6. In combination in a conduit form, outer and inner sectional forms, and removable plates releasably carried between the opposing ends of the sections of one of the forms and adapted to support water stop members.
7. In combination in a conduit form, outer and inner sectional forms, and removable sectional rings clamped between the opposing ends of the sections of one of the forms and adapted to engage and support water stop members lying between the joints.

CHARLES D. McARTHUR.
